UNITED STATES PATENT OFFICE.

JOHN L. MALONEY, OF BELLAIRE, OHIO, ASSIGNOR OF ONE-FIFTH TO
THOMAS MORAN, OF BELLAIRE, OHIO.

MACHINE FOR FORMING SHEET-GLASS.

No. 839,168.

Specification of Letters Patent.

Patented Dec. 25, 1906.

Application filed July 12, 1906. Serial No. 325,909.

To all whom it may concern:

Be it known that I, JOHN L. MALONEY, a citizen of the United States of America, and a resident of Bellaire, county of Belmont, 5 and State of Ohio, have invented certain new and useful Improvements in Machines for Forming Sheet-Glass, of which the following is a specification.

My invention relates to new and useful improvements in machines for forming sheet-glass; and it has for its chief object to provide a machine for forming sheet-glass which is provided with means whereby the temperature of the metal passing therethrough and 15 the temperature of the rolls may be regulated.

A further object of the invention is to provide a gravity-fed machine of the character mentioned which is adapted to produce 20 sheets of glass of an even thickness throughout.

With these and other objects in view my invention finally consists in the particular construction, arrangement, and combination 25 of parts, which will hereinafter be fully described, reference being had to the accompanying drawings, forming a part of this specification, in which—

Figure 1 is a side elevation of the invention. Fig. 2 is a front elevation of the same. Fig. 3 is a section on the line 3-3, Fig. 1. Fig. 4 is a perspective view of a hopper for containing lubricating material. Fig. 5 is a perspective view of the shaping-clamp, and Fig. 35 6 is a cross-section of the glass-pouring spout.

Referring to said drawings, in which like reference - numerals designate like parts throughout the several views, 1, indicates a frame supported at its rear side by or against 40 the wall of the melting-furnace. Suitably mounted in the wall of said furnace at a proper point is a metal-pouring spout 2, beneath which said frame 1 is located. Journaled in said frame 1 is a series of sets of rolls 45 arranged in vertical alinement, each set comprising a roll 3, journaled in stationary bearings 4, and a roll 5, journaled in movable bearings 6, the latter movable in longitudinal guide-grooves 7, provided in the side rails 8 of 50 said frame. The under side of each movable bearing 6 is provided with a tongue 9 for sliding in the groove 7, and on the outer end of each movable bearing is a lug 11, in which is revolvably mounted or swiveled the end of

an adjusting-screw 10, which is projected 55 through a threaded opening in a stationary lug 12, mounted upon the side rail 8. By manipulating said adjusting-screws 10 the relative distance between the rolls 3 and 5 may be regulated to govern the thickness of 60 the sheet of glass being formed. The ends of the rolls 3 are provided with flanges 13, which slightly overlap the ends of the rolls 5 to close the ends of the space between said rolls. 65

Rigidly mounted on the opposite ends of the top of the frame 1 are supports 14, on which is pivotally mounted a longitudinal plate 15, which normally stands slightly tipped backward, as shown in Fig. 1, said 70 plate forming one of the jaws of a metal-shaping clamp 16. The opposite jaw of said clamp consists of a plate 17, similar to the plate 15, pivotally mounted at each end upon rods 18, which are pivoted at their lower ends 75 in lugs 19, mounted upon said frame 1. A suitable handle 20 is secured to the plate 17, by means of which said plate is forced forward to flatten the edge of the molten body of glass as it begins to pour from the spout 2. 80 As is obvious, by forcing the plate 17 forward the front end of the molten body is flattened between said pivoted plates, which when forced together assume substantially vertical positions, so that it is readily received between the upper rolls 3 and 5. The plate 17 having been forced forward is immediately 85 withdrawn to permit the metal to pass between the jaws of the clamp to the rolls without hindrance or interruption. The different sets of rolls which are driven by belts 21, connected with suitable driving mechanism, are not intended to serve as means for conveying the metal downward, but are intended to shape the metal and to form a 95 sheet of an even thickness throughout, the metal being carried downward by gravity. 90

Located on each side of the rolls are two pipes 22 and 23, one for cold air and the other for hot blasts, and connected with said pipes are branch pipes 22' and 23', which extend inward over each set of rolls and have on their inner ends pipes 22^a and 23^a, respectively, which lie parallel to the rolls at each side of the path of travel of the metal. Each 100 of said pipes 22^a and 23^a is provided with a line or row of perforations (designated 22^b and 23^b) in the face thereof, through which 105

rations, respectively, cold and hot blasts may be directed upon the metal to regulate the temperature thereof. Valves 22^c and 23^c are provided in the branch pipes 22^c and 23^c, 5 as shown. Also connected with said pipes 22 and 23 are branch pipes 22^d and 23^d, which carry upon their ends perforated pipes 22^e and 23^e, through which, respectively, cold and hot blasts of air may be directed upon the rolls to regulate the temperature thereof. Having passed through the last or lower set of rolls, the metal may be cut into sheets by any of the various methods ordinarily employed for the purpose, after which said 5 sheets are permitted to slide down an incline 24 to a suitable point for handling.

The spout 2 is mounted at a point to receive the metal from the pouring-mouth 25 of the furnace, and it has pivotally mounted 20 in one of its sides 26 a lever 27, from the inner end of which depends a heavy block 28, preferably of tiling, which when lowered upon the bottom of the spout effectually closes said mouth 25 and prevents the flow of metal 25 from the furnace. By means of said lever the block is raised or elevated to allow the metal to flow through the mouth, and by adjusting the height to which said block is elevated the rate of the flow of the metal is 30 regulated.

Mounted upon supports 29, attached to the frame 1 over each roll or at opposite sides of the path of travel of the metal through the rolls, is a hopper 30 for holding a suitable 35 lubricating material, such as sawdust or ground wood, and for feeding said material

to the rolls through the feed-opening 31 thereof.

Having thus fully described my invention, what I claim as new, and desire to secure by Letters Patent, is-

1. In a device of the character described, the combination with a glass-melting furnace, of a frame mounted in juxtaposition to the furnace beneath the pouring-mouth 45 thereof, a plurality of sets of vertically-aligned rolls mounted on said frame, means for adjusting the rolls of each set with relation to each other, a metal-shaping clamp above the upper set of rolls, and a series of blast-pipes 50 arranged for regulating the temperature of the rolls and of the metal passing therethrough:

2. In a device of the character described, the combination with the glass-melting furnace, of a frame mounted in juxtaposition to the furnace beneath the pouring-mouth 55 thereof, a plurality of sets of vertically-aligned gravity-fed rolls, mounted on said frame, a metal-shaping clamp, a series of 60 suitably-arranged blast-pipes, whereby the temperature of the rolls and of the metal passing through the rolls may be regulated and valves for controlling the blasts emanating from said pipes. 65

Signed by me in the presence of two subscribing witnesses.

JOHN L. MALONEY.
